Primary Examiner — Karen E Kearney*Assistant Examiner* — John Reickel(74) Attorney, Agent, or Firm — Ladas & Parry LLP(57) CLAIM

The ornamental design for a display screen or portion thereof with graphical user interface, as shown and described.

DESCRIPTION

The sole FIGURE is a front view of a display screen or portion thereof with graphical user interface showing our new design. The broken line showing of the display screen and user-interface elements are included for the purpose of illustrating portions of the article and form no part of the claimed design.
